UNITED STATES PATENT OFFICE.

JOHN HEINEN, OF ATCHISON, KANSAS.

LIFTING-JACK.

1,345,178.

Specification of Letters Patent. Patented June 29, 1920.

Application filed January 29, 1920. Serial No. 354,991.

To all whom it may concern:

Be it known that I, JOHN HEINEN, a citizen of the United States of America, and resident of Atchison, in the county of Atchison and State of Kansas, have invented certain new and useful Improvements in Lifting-Jacks, of which the following is a specification.

This invention relates to hoisting devices and particularly to lifting jacks, the said invention having for its object the provision of a lifting lever and handle, the combined handle and lever being foldable so that the handle can be moved out to increase the leverage and then moved back parallel with the load engaging member of the lever, novel means being also provided for holding the lever at different positions of adjustment.

A further object of the invention is to provide novel means whereby the lever retaining member is held against movement beyond a predetermined degree in one direction, the said device consisting of comparatively few parts of simple and inexpensive construction.

With the foregoing and other objects in view, the invention consists in the details of construction, and in the arrangement and combination of parts to be hereinafter more fully set forth and claimed.

In describing the invention in detail, reference will be had to the accompanying drawings forming part of this specification wherein like characters denote corresponding parts in the several views and in which—

Figure 1 is a view in elevation of the lifting jack embodying the invention;

Fig. 2 is a top plan view thereof; and

Fig. 3 is a side elevation with the parts in folded positions.

In these drawings, 5 denotes a base having a standard 6 rising therefrom, the said standard being bifurcated at its upper end to form a clearance for the reception of the load engaging lever 7, which element 7 is oscillatably mounted on the pivot 8 extending through apertures 9 and 10 in the bifurcations of the standard.

The base 5 has a lug portion 11 carrying a pivot 12 in which a link 13 is pivoted, the said link having a lug 14 projecting from one side thereof downwardly and adapted to engage a flange 15 of the base 5 so that oscillatable movement of the link in one direction is limited, by reason of the fact that the

lug 14 will engage the flange and support the link.

The upper end of the link is bifurcated, and the load engaging lever 7 extends between the furcations of the lever, and the said member 5 is adapted to engage the link 13 at the bottom of the space between the furcations to force the link into position parallel with the standard, as is shown in Fig. 3.

One edge of the link has a series of projections 16 in spaced relation to each other, and these projections are adapted to engage a pin 19 according to the degree of elevation of the load engaging member, and the relation of parts is such that the base is operative to retain the jack in an upright position when the said load engaging member is in use.

At the outer end of the load engaging member, there is an upwardly extending lug 20 which carries a pivot 21 on which the handle or lever 22 is oscillatable, the said handle or lever at its inner end being recessed to form a clearance for the outer end of the load engaging lever or member, so that when the parts are in the position shown in Fig. 1, pressure on the outer end of the handle will result in the manipulation of the load engaging member to lift the load and when lifted, the link will adjust itself by gravity and swing outwardly into engagement with the pin. The upper surfaces of the projecting members are inclined so that they form camming surfaces which will tend to move the link rearwardly when pressure is applied in the act of lifting the load, and thus the pin 19 can move with relation to the projections from one to the other downwardly and the link will automatically engage the pin to hold the parts in the different positions of adjustment, owing to the fact that it will swing outwardly at the top by gravity.

I claim—

1. In a lifting jack, a base having a standard, a load supporting member pivotally connected to the standard, a pin extending transversely of the load engaging member, a link pivotally connected to the standard and having means for engaging the pin, a lug at the lower end of the link engaging the base for holding the link against movement in one direction, and means for exerting pressure on the load engaging member.

2. In a lifting jack, a base having a standard, a flange on the base, a link pivotally connected to the base, a lug extending from the link and adapted to engage the flange
5 for limiting the movement of the link, a load engaging member pivotally connected to the standard, a device on the said load engaging member engageable for holding the load engaging member at predetermined positions, and a lever pivotally connected to the said load engaging member.
3. In a lifting jack, a base, a standard rising therefrom, a load engaging member pivotally connected to the standard, a link

pivots connected to the base, said link 15 having a bifurcated upper end to receive the load engaging member and adapted to be engaged by the load engaging member for holding the link parallel with the standard, projections on the link, a pin on the load 20 engaging member adapted to be engaged by the projections for holding the load engaging member at different positions of adjustment, and a lever pivotally connected to the said load engaging member.

JOHN HEINEN.

Witness:

JOHN N. ERNGEN.
